CASS A. BUDNIK, OF ROCKPORT, WASHINGTON

SELF-SUPPORTING DAM-BUILDING TOWER AND PROCESS

Application filed September 4, 1929. Serial No. 390,232.

My invention relates to dam building and like large concrete construction work.

It is current practice in such work, especially where the dams are of considerable height and width, to build a number of towers within the dam site of steel. These towers are of skeleton construction and at times will run three hundred to five hundred feet in height, it being necessary that they 5 extend well above the ultimate top of the dam. Naturally, they must be strongly guyed at intervals, and heavy steel cables are employed for the purpose. Upon these towers are supported cable-ways or conveyors, by 10 means of which the concrete is delivered from a mixing plant on the bank across the face of the dam and ultimately deposited in the forms. It is becoming recognized that the 15 dam is made stronger in proportion as the concrete is the least disturbed in its handling between the mixing plant and the place of deposit, and to obtain this result, it is becoming the practice to employ belt conveyors, which in practice, are not usually made in 20 units of greater length than one hundred feet, hence, it would be necessary to provide 25 towers at not to exceed one hundred foot intervals, and it may readily be appreciated that the expense of such towers, and their 30 guy wires, in particular, will constitute a major item of the cost of a dam. Such a cost may run to 15% or 20% of the total cost of 35 the dam, and the towers are ordinarily left imbedded in the concrete, or if they are so positioned that they may be dismounted and 40 taken down, it will be found that they are unsuitable for any construction work liable to occur in the immediate future and must either be stored or disposed of as junk. Similarly, the cables having been in use over a 45 period of some little time and being cut to fit and serve as the guy wires, cannot readily be put to another use and their value is largely lost.

My invention has as its major object the provision of a method and apparatus whereby the towers or supports for the conveyors and for the concrete handling and distributing mechanism, may be supported not from 50 the bed of the dam, but from elements in-

corporated in the dam itself, such as foundation blocks of concrete, which can be formed in place with little difficulty or expense and left in place, ultimately forming part of the homogenous mass of concrete.

55

A further object is the provision of means whereby the towers themselves, which may be of steel, are in effect, elevated from such foundation blocks, being kept always above the working level of the dam, whereby as the 60 work progresses they are always on top of the dam and when it is finished they may be removed and lowered and used again, being made up in standard sizes and not necessarily 65 to fit the height of the particular dam under construction.

It is my object to provide a mechanism of the general character indicated, which may be securely supported in the dam itself or upon foundation blocks, and which will not 70 require guy wires.

It is a further object to provide such mechanism with which may be associated concrete handling and distributing mechanism so arranged that there need be no danger of 75 upsetting the tower or disturbing its equilibrium.

Other objects, and especially such as refer to details of my method and apparatus, may be ascertained more readily from a study of 80 the drawings, the specification and claims of this application, and such details form more especially the subject matter of a companion application, Serial No. 401,177, filed October 21, 1929.

85

My invention comprises the novel method and the novel apparatus or structure, as shown in the accompanying drawings, described in the specification, and more particularly defined by the claims which terminate 90 the same.

In the accompanying drawings I have shown in a more or less diagrammatic way apparatus by means of which my process may be carried out.

95

Figure 1 is a general elevation of my apparatus in operation.

Figure 2 is a diagrammatic showing of three adjoining towers forming parts of my apparatus, the three towers being illustrated 100

in three successive positions, according to my process.

A description of the particular apparatus illustrated will make clearer my process, and I will then point out the principles underlying the same.

As seen in Figure 1, an inner tower 1 is disposed within an outer tower 2, each being of skeleton construction, so that each slides vertically upon and relative to the other. These towers are supported primarily from a foundation block 3, the first of these foundation blocks will rest upon bed rock of the dam site, while succeeding blocks will rest one upon the other. These may be cast in place within the inner tower 1, and it will be understood that both towers have their bottoms freely open so that they may move vertically relative to the foundation block represented at 3. However, they are supported upon this foundation block, for instance, by means of bars 30, which extend through holes provided near the upper edge of the foundation block 3, and which project therefrom under the lower edges of the towers. Additional pins 31 may be provided, these being somewhat shorter than the pins 30, and extending only beneath the bottom of the inner tower 1, rather than under both towers. The pins 31, therefore, may support the inner tower in elevated position and the outer tower 2 may move vertically outside of the ends of these pins 31 until it is in position to be supported by the pins 30.

For a reason which will be made clear hereafter, I prefer that one of these towers (as shown, the outer tower 2) be secured positively to the foundation block 3, and for this purpose I have shown jacks 33, disposed horizontally below the bottom of the tower 1 and threading in plates 32, secured to the tower 2, and arranged to clamp against the upper side faces of the foundation blocks. These jacks may be of any suitable type, those shown being merely illustrative of a means which will positively secure the outer tower 2 to the foundation block to prevent side sway.

Various means may be provided for elevating the towers 1 and 2. I have shown a winch, generally indicated by the numeral 4, supported upon a platform 10 of the inner tower, which winch carries a line 42. This line passes under a pulley or guide 41, provided on the inner tower 1, and the end of the line 42 is anchored at 44 to the top of the outer tower 2. The line 42 may, of course, be provided with various means for increasing its lifting powers, but the showing is to be understood as purely diagrammatic. Winding in on the line 42, then, will cause the inner tower 1 to be lifted, the weight being borne by the line 42, of which there is preferably one extending upward at each side of the composite tower, and through this line 42 the inner tower 1 is supported from the outer tower

2, and indirectly, of course, from the foundation block 3, upon which the tower 2 rests.

A second winch 5, is also shown supported upon the platform 10, and from this winch 5 run lines 52 direct to pulleys 51 in the top of the inner tower 1 and thence to an anchorage at 53 upon the outer tower 2. By means of this line the outer tower 2 can be elevated from the inner tower 1, which at such times, is supported from the foundation block 3.

It will be understood that various means for handling and distributing the concrete would be supported from the composite tower thus formed. For instance, a conveyor 6 delivers concrete to the tower, whence it may be passed on to another conveyor 60 by means of a chute arranged between the ends of the two conveyors, as will be apparent, or the concrete from the conveyor 60 may be delivered into a hopper 61, supported in the inner tower 1, and thence delivered by chutes, such as 62 or 63, to points where it is to be placed. There may be provided upon the outer tower 2 a circular hopper or chute 64, into which concrete from the chute 62 is delivered and from which it is delivered to conveyors as 70 and 71, supported upon a boom 7, which is carried upon the outer tower 2. This tower may revolve about the boom upon bearing rings 27 at top and bottom, and the boom may be provided with an extension 72 opposite the main boom 7, upon which a counterweight 73 may be slidable, this counterweight being connected by mechanism, which need not be here described, and such as is shown in the companion application referred to. Its function is to counterbalance the weight of the shiftable conveyor 71 and the concrete carried thereby. By these or equivalent means, the booms 7 and 72 may be kept substantially in equilibrium to minimize the side sway of the tower 2, and such side sway as occurs is taken up by the clamping jacks 33 heretofore described.

It is believed that my process will by now be readily understandable. A concrete foundation block 3 is first cast in place upon the bedrock indicated by the line L of Figure 2. The inner tower 1 and outer tower 2 may likewise rest upon the bedrock. This relationship is shown at the right in Figure 2. The next step, preferably, is in preparation for a subsequent move, and may consist of casting in place within the tower 1, and resting squarely upon the first block 3, a second foundation block indicated by the numeral 3A. The purpose in casting this prior to any other step is to give it sufficient time to set and cure, so that it may support the weight of the tower when the tower is ready for a further upward shift. The concrete for casting the block 3A may be supplied through the chute 63 heretofore mentioned.

With the block 3A cast, the next step is to elevate the complete tower above the work-

ing level L, and this is done by elevating one of the towers, bearing upon the other; for instance, the inner tower 1, which is preferably slightly greater in elevation than the outer tower 2, is lifted first. This inner tower is elevated by the winch 4 or equivalent means, and is supported in elevated position upon the bars 31. Parts are illustrated in this position in the middle tower of Figure 2 and it will be observed that the chute 62 is retracted or telescoped at this time to prevent its being fouled with parts of the outer tower 2.

Now the next step is to raise the outer tower 2 from the inner tower, which has already been raised. The winch 5 is brought into operation and the outer tower 2 is raised until its bottom is substantially on a level with the bottom of the inner tower 1, whereupon the pins 30 are inserted, and the tower has been raised substantially the height of the foundation block 3. It will be understood, of course, that suitable provision is made in the casting of these blocks for the reception through them of the bars 30 and 31. Now with the towers 1 and 2 resting upon the respective bars 31 and 30, the device is ready for depositing concrete upon the working level L up to substantially the level of the bars 30 and 31, but I prefer that the first step be the casting in place upon the block 3A of a third foundation block 3B, so that this may have time to set and cure before it is needed to support the weight of the towers. The block 3A by this time will have set sufficiently to support the weight of the block 3B.

Now the concrete is deposited or distributed by the means heretofore indicated, and when the fresh concrete deposited around the foundation block 3 has reached substantially to the level of the lower ends of the towers 1 and 2, these towers are again lifted as described before, and use the block 3A as the new support, leaving only the block 3 embedded in the concrete.

Various means may be employed for raising the towers 1 and 2, and as a matter of fact it is not at all essential that these telescope one within the other, but only that they be relatively movable vertically and that each be capable of raising the other, and either independently or mutually self-supporting. So far as this present application is concerned, the concrete handling and distributing means is immaterial, and may be any which is found suitable or desirable. The essence of the present invention consists in the elevation of one tower from the other in succession and the supporting of the towers upon foundation blocks, which are inexpensive and which it is intended shall be embedded ultimately in the concrete of the dam, always keeping the towers above the working level.

What I claim as my invention is:

1. The process of placing concrete in dams

or the like through the employment of two tower sections of such base area and height as to be self-supporting, said sections being telescoped and vertically movable relative to each other, which consists in casting a foundation block upon the substructure, raising one of said tower sections and supporting it in elevated position from said block, raising the other section and supporting it likewise in elevated position upon the same block, and supplying concrete to the elevated tower for local distribution, repeating the casting, raising and distributing operations until the dam has reached the required height.

2. The process of placing concrete in dams or the like through the employment of two telescoping tower sections, each of such base area and height as to be self-supporting, which process consists in casting a foundation block within the base of the inner section, raising one of said sections and supporting it in elevated position upon said block, raising the other section and supporting it from said block, in elevated position, and supplying concrete to the elevated tower for local distribution.

3. The process of placing concrete in dams or the like through the employment of two telescoping tower sections, which process consists in first casting a foundation block upon the substructure within the base of the inner tower section, then raising the inner section from the outer, as the latter rests upon the substructure, supporting the inner section in elevated position upon said block, then raising the outer section from said inner section and supporting the outer section in elevated position from the block, and finally supplying concrete to the elevated tower for local distribution and for the casting of a new foundation block.

4. The process of placing concrete in dams or the like through the employment of telescoping inner and outer tower sections, which process consists in first casting a foundation block upon the substructure within the base of the inner section, then raising the inner section from the outer, resting upon the substructure and supporting it in elevated position upon said block, then raising the outer section from said inner section and supporting it in elevated position from the block, then anchoring the outer section upon the block to minimize side sway, and finally supplying concrete to the elevated sections for local distribution and for the casting of a new foundation block.

5. The process of placing concrete in dams and the like through the employment of a tower, which consists in casting a foundation block of concrete within the area and above the working level of the dam, and thereafter raising the tower thereupon above the working level, supplying concrete to the

tower and distributing it thereabout to embed the block and raise the working level, and meanwhile casting upon the first block a second upon which the tower can again be raised to repeat the cycle.

6. In a structure of the character described, for use in conjunction with a foundation block to be left in place, a tower, means bearing upon said block for elevating said tower to position it above the working level, means to support said tower upon the same block in elevated position, and means upon said tower for distributing concrete within a circle about said tower.

15. 7. A structure of the character described, comprising two associated towers, means for elevating either tower from the other, independent means for supporting each of said towers from a common foundation block in position elevated above the work level, and concrete handling devices supported on said towers.

25. 8. In a structure of the character described, an inner tower and an outer tower telescoping therewith, means for supporting said towers from a foundation block for vertical movement of one relative to the other, and means for successively elevating said towers and for supporting them in elevated position from said foundation block.

25. 9. In a structure of the character described, an inner tower and an outer tower each guided on the other for relative vertical movement, means for supporting each of said towers upon a foundation block, means for elevating each tower in succession from the other tower, and means for supporting the towers from said foundation block in elevated position.

40. 10. In a structure of the character described, an inner tower and an outer tower each guided on the other for relative vertical movement, independent means for supporting each of said towers from a foundation block, means upon the inner tower and bearing upon the outer tower for elevating the inner tower, means also carried by the inner tower for elevating the outer tower, and means for supporting each tower at the new level, from the foundation block.

45. 11. A structure as defined in claim 10, including additional means for securing at least one of said towers to the foundation block, to prevent side sway.

50. 12. A structure as defined in claim 10, including additional means for securing the outer tower to the foundation block, and concrete handling devices supported from said outer tower.

60. 13. A dam building tower, including, in combination, a pair of complemental tower sections, each of a base area and height to be self-supporting, and means for raising each section from and relative to the other, as the latter rests upon its base.

14. A dam building tower including, in combination, an inner and an outer tower section, guide means permitting telescoping of each section relative to the other, means on the inner section for raising the outer section relative to the inner, as the outer section rests upon a foundation, and means for raising the inner section relative to the outer, when the inner section in turn rests upon a foundation.

15. A dam building tower comprising, in combination, a pair of complemental tower sections, means for raising each section from and relative to the other, as each section in turn rests upon a foundation, and means for handling materials associated with the composite tower.

16. A dam building tower comprising, a combination, a pair of complemental tower sections of less height than the dam to be built, means for raising each section from and relative to the other, as each section in turn rests upon a foundation, means for receiving and means for distributing concrete associated with the tower.

Signed at Rockport, Washington this 27th day of August, 1929.
